HULLER TYPE GIN WITH FIRE FRONT

Jeffrey J. Wallace, Amite, La., assignor to Gullett
Gin Company, Amite, La., a corporation of
Louisiana

Application December 5, 1940, Serial No. 368,706

12 Claims. (Cl. 19—56)

This invention relates to improvements in cotton gins of that type in which the cotton is fed first to a huller breast before entering the roll box, and it has for one of its objects the provision of a swingably suspended front for the huller breast which when in normal closed position guides cotton, descending from the feeding spout, into the mouth of the hulling chamber, and which when swung to open position stands out of the way of the column of descending cotton so that the latter impinging first against the outside wall of the roll box, is deflected so as to by-pass the mouth of the hulling chamber and is discharged upon the floor in front of the gin.

This is desirable when foreign matter is delivered to the gin in the cotton, or in case of fire that may have originated in other parts of the cotton ginning outfit, to prevent the fire entering the gin.

Another object of the invention is to provide, in a huller gin of the type described, including the usual huller drum and conveyor, in the hulling chamber, of a swinging breast front as described, having a baffle, and a screen beneath the conveyor with a guard member hinged at the outer edge of the screen and having a portion adjacent the lower end of the baffle forming a substantial continuation of said baffle when the breast front and the hinged guard member are both in closed position, for guiding the cotton to the huller drum, said guard member being swingable to open position after the breast front has been swung open or bodily removed, giving access to the space between the conveyor and screen so that foreign matter may readily be cleared from said space.

A further object of the invention is to provide for adjustment of the huller drum to and from the saws, to carry the usual bristle board which cooperates with the huller drum, on the guiding portion of the hinged guard member, and to provide operating means between said huller drum and said hinged guard member whereby the latter, and with it the bristle board, will be moved simultaneously with the huller drum, in the adjustment of the latter, so as to keep the bristles substantially the same distance from the huller drum in all positions of its adjustment.

Other objects of the invention will appear as the following description of a preferred and practical embodiment thereof proceeds.

In the drawings which accompany and form a part of the following specification, and throughout the several figures of which the same char-

acters of reference have been employed to designate identical parts:

Figure 1 is a vertical side section through that portion of a cotton gin of the huller type which embodies the subject invention, the breast front and hinged member being shown in closed co-operable positions;

Figure 2 is a similar view, unessential parts being omitted, showing the front and hinged guard member in opened swung positions;

Figure 3 is a vertical cross-section taken along the line 3—3 of Figure 1, viewed in the direction of the arrows;

Figure 4 is a side view in elevation of the 15 levers and linkage constituting the adjusting means between the shaft of the huller drum and the cam shaft which adjusts the position of the hinged guard member and the bristle board carried thereby;

Figure 5 is a horizontal section taken along the line 5—5 of Figure 2, showing the detents for maintaining the swinging front in openly swung position; and

Figure 6 is a horizontal cross-section taken 20 along the line 6—6 of Figure 1 showing the detents which hold the front in closed position.

Referring now in detail to the several figures, the numeral 1 represents in general a cotton gin of the huller type having the saw cylinder 2 with the saws 3, which normally extend between the ribs 4 and 5 of the respective ginning and hulling breasts 6 and 7. The inner or ginning breast 6 is pivoted to the gin frame at 8, while the outer or hulling breast is pivoted to 30 the inner breast at 9. The upper parts of the two breasts define the roll box 10.

The outer breast has the opposite side walls 11 and 12, the upper rear wall 13 which forms the outer or movable side of the roll box, the lower 40 rear wall 14 which includes the huller ribs 5, and bottom and forward structure comprising the screen 15 and the guard member 16, the latter being hinged at 17 adjacent the front end to the screen. The lower portions of the side walls, together with the lower rear wall, the screen 15 and the hinged member 16 define a hulling chamber in the lower part of the outer breast in which is located the conventional huller drum 18, and beneath it the conveyor 19. The lower 45 part of the conveyor rotates in close proximity to the screen 15, the latter having a concave shape corresponding to the shape of the conveyor.

The mouth of the hulling chamber is represented by the dotted line a, b, and lies in a plane

extending in a downward and outward direction.

The upper rear wall 13 of the outer breast also inclines downwardly and outwardly and is in the path of the gravitational descent of cotton delivered from suitable feeding means located above the open top of the huller breast. When the cotton strikes the downwardly and outwardly inclined surface of the wall 13, it is deflected into a trajectory, the path of which by-passes the mouth *a, b*, of the hulling chamber.

The outer breast 7 is provided with a front 20 which extends between the side walls 11 and 12 and is hingedly suspended along an axis 21 located at some distance above the mouth of the hulling chamber. The front 20 is free to swing open from the bottom about the axis 21. The front 20 is provided with spring detents 22 and 23 on each side adjacent its lower end, which detents cooperate with corresponding recesses 24 and 25 formed in the side walls of the huller breast. When the front 20 is in the closed position shown in Figure 1, the detents 22 and 23 have sprung into the recesses 24 and 25, thereby holding the front firmly in closed position. By grasping the rod 26 which forms the bottom edge of the front 20, at any point transversely of the front, one may swing the front outwardly, releasing said detents.

Near its upper end the front is provided on both sides with the laterally projecting spring detents 27 and 28. These normally abut against the smooth sides of the huller breast when the front is in closed position, but when it is swung out sufficiently, as indicated in Figure 2, said detents slip beyond the edges of the side walls 11 and 12 and project against the ends of said side walls, holding the front in outwardly swung position. It may be closed by pushing against the lower bar 26 so as to depress said detents by camming them against the edges of the side walls 11 and 12.

It will be observed from Figure 1 that the front 20 has an inwardly and downwardly inclined baffle 29 which extends transversely between the side walls of the huller breast and terminates adjacent the mouth of the hulling chamber. This baffle is in the path of the trajectory of the column of cotton deflected by the inclined wall 13, and guides the cotton to the mouth of the hulling chamber. When the front 20 is in its outwardly swung position shown in Figure 2, the baffle 29 is removed from the path of the descending column of cotton so that the latter, deflected by the wall 13, is unobstructed in its passage through the breast, and is discharged upon the floor in front of the gin without having passed into the hulling chamber. Should a foreign body such as a sack come down with the cotton, or should the cotton be on fire when it reaches the gin, the front 20 may be quickly swung to its open position, preventing the sack or the fire, as the case may be, from getting into the mechanism of the gin.

The upper end 30 of the hinged member 16 is inwardly and downwardly inclined toward the huller drum 18, and when the front 20 and hinged member 16 are both in closed position, the inner end 30 of the latter member forms a substantial continuation of the baffle 29 in guiding the cotton toward the huller drum. Said inner end 30 forms an advantageous as well as convenient support for the bristle board 31 carrying the usual row of bristles 32 which cooperate with the huller drum. The hinged

member 16 is biased towards closed position by a spring 33 which is preferably bent into a loop having one end anchored to a lug 34 on the back of the hinged member 16 adjacent the hinge 17, and having its other end anchored to the side wall of the breast. It is contemplated that there shall be two such springs, one at each side of the hinged member 16. When the hinged member is swung to the opened position shown in broken lines at 16' in Figure 2, the spring moves bodily to the dotted line position indicated at 33' in Figure 2 where it is ineffective in closing the hinged member, so that the latter lies open as shown. In all intermediate positions the spring 33 urges the hinged member to close.

The hinged member may be opened after the front 20 has been swung to its open position or after it has been bodily removed. Removal of the front is accomplished by means of the slot connection 35 by means of which it is suspended from the axis 21. The purpose of opening the hinged member 16 is to permit the space between the conveyor 19 and screen 15 to be cleared of the accumulation of foreign matter.

It is customary to provide an adjustment for moving the huller drum toward or away from the gin saws in order to secure optimum efficiency of ginning due to the character of staple and other factors, and it is essential or at least desirable, that the bristle board should be likewise adjustable so that the bristles can maintain their proper distance relationship with respect to the teeth of the huller drum in all positions of adjustment of the latter. With this end in view, I have provided for simultaneous adjustment of the huller drum and bristle board, as follows. Figure 4 shows a manual operating lever 36 which is pivotally mounted on the outside of one of the side walls of the cotton gin, for example, the side wall 12. This has a suitable detent 37 which coacts with a rack 38 for holding the lever 36 in any position of adjustment. The lower end of this lever is suitably keyed to a shaft 39 which passes transversely through the shaft inside of the hinged member 16 and has its opposite ends journaled in the opposite side walls 11 and 12. This shaft is provided with cams 40 which bear against the inner side of the hinged member 16, and when the shaft is turned in the direction of the arrow shown in Figure 1, the cams press outwardly against the hinged member 16, moving it outwardly against the closing bias of its spring 33. As the hinged member 16 moves outwardly, it carries with it the bristle board 31 and the row of bristles 32. When the shaft 39 is moved contra to the direction of the arrow in Figure 1, the cams 40 recede, permitting the spring 33 to move the hinged member 16 in its closing direction.

In addition to turning the shaft 39, the lever 36 is concerned with operating a set of mechanism which is duplicated on opposite sides of the huller breast. One set only will, therefore, be described. This consists of a bearing 41 carrying the end of the shaft 42 of the huller drum and movable in a slot 43 in the side wall 12 of the huller gin. This bearing is part of a lever 44 which is pivoted at 45 to the side wall 12. The lever 44 is oscillated by a link 46 pivotally connected at one end to said lever and at the other end to the operating lever 36. When the operating lever moves to the right, as shown in

Figure 4, the shaft 39 turns clockwise and the lever 44 oscillates to the right. Thus, simultaneously with the translatory movement of the huller drum away from the gin saws, the hinged member 16 and with it the bristle board and bristles is moved to the right by the clockwise turning of the shaft 39. When the lever 36 is moved toward the left, the lever 44 oscillates toward the left, bringing the huller drum closer to the saws. Simultaneous with this movement the shaft 39 is turned in a counterclockwise direction, causing recession of the cams and movement of the hinged member 16 in a closing direction under the urge of its spring 33. This causes the bristle board and bristles to follow in the direction of adjustment of the huller drum. Thus, by the above adjustment the distance of the bristles from the huller drum is kept substantially constant throughout the range of adjustment of the huller drum.

In Figure 4 is shown a link 47 carrying a roller 48 which bears against the chain 49 that drives the huller drum. This is simply a conventional chain tightener for taking up slackness in the chain produced by the adjustment of the huller drum in a direction away from the saws.

It will be understood from the above disclosure that I have provided a simple and effective means for by-passing the cotton while being fed to the gin, past the mouth of the hulling chamber, which may be operated with the quickness and dispatch essential in an emergency; that I have also provided an effective means for giving access to the screen and conveyor for removing obstructions or accumulations of foreign matter, and that I have employed these means as an adjunct in providing simultaneous adjustment of the huller drum and bristle board when the latter is adjusted towards or from the gin saws.

It will be obvious to those skilled in the art that the specific details of construction and the arrangement of parts as shown and described are by way of example and not to be construed as limiting the scope of the invention which is defined in the appended claims.

What I claim as my invention is:

1. Cotton gin of the huller type having inner and outer breasts defining between them a roll box, the outer breast having side walls and a lower rear wall including the huller ribs, and having bottom and forward enclosing structure, the lower parts of said side walls cooperating with said lower rear wall and said bottom and forward enclosing structure to form a hulling chamber having its mouth in a downwardly and forwardly inclined plane, a huller drum in said hulling chamber, said outer breast having an upper rear wall in the path of cotton received from a feeding means and inclined so as to direct the cotton in a trajectory which in the absence of opposing structure will by-pass the mouth of said hulling chamber, a front for said outer breast pivotally suspended at its top at a point above said mouth, having an inwardly and downwardly inclined baffle on its inner side for deflecting the column of cotton into said mouth when the front is closed, said front being swingable outwardly to a non-obstructing position permitting the cotton to by-pass said mouth, said enclosing structure including an outwardly swingable portion hinged at its lower end, having its upper end portion inwardly and downwardly directed and adjacent the lower end of said baffle when said

front and said hinged member are closed, forming a continuation of said baffle.

2. Cotton gin as claimed in claim 1, including a bristle board carried by said upper end portion of said hinged member having its bristles in operative proximity to said huller drum.

3. Cotton gin of the huller type having inner and outer breasts defining between them a roll box, the outer breast having side walls and a lower rear wall including the huller ribs, and having bottom and forward enclosing structure, the lower parts of said side walls cooperating with said lower rear wall and said bottom and forward enclosing structure to form a hulling chamber having its mouth in a downwardly and forwardly inclined plane, a huller drum in said hulling chamber and a conveyor in said hulling chamber below said huller drum, said outer breast having an upper rear wall in the path of cotton received from a feeding means and inclined so as to direct the cotton in a trajectory which in the absence of opposing structure will by-pass the mouth of said hulling chamber, a front for said outer breast pivotally suspended at its top at a point above said mouth, having an inwardly and downwardly inclined baffle on its inner side for deflecting the column of cotton into said mouth when said front is closed, said front being swingable outwardly to a non-obstructing position permitting the cotton to by-pass said mouth, said enclosing structure including a screen beneath said conveyor and an outwardly swingable member hinged at its lower end adjacent said screen, having its upper end portion inwardly and downwardly directed and adjacent the lower end of said baffle when said front and said hinged member are closed, forming substantially a continuation of said baffle.

4. Cotton gin as claimed in claim 3, including a bristle board carried by the upper end portion of said hinged member having its bristles in operative proximity to said huller drum.

5. Cotton gin of the huller type having inner and outer breasts defining between them a roll box, the outer breast having side walls and a lower rear wall including the huller ribs, and having bottom and forward enclosing structure, the lower parts of said side walls cooperating with said lower rear wall and said bottom and forward enclosing structure to form a hulling chamber, a huller drum in said hulling chamber cooperative with gin saws projecting between the huller ribs, and a conveyor in said hulling chamber below said huller drum, said enclosing structure including a screen beneath said conveyor and an outwardly swingable member hinged at its lower end adjacent said screen, having its upper end portion inwardly directed toward said huller drum, a bristle board carried by said inwardly directed end having its bristles in operative proximity to said huller drum, a spring biasing said hinged member toward its closed position, and means for simultaneously adjusting said huller drum away from said saws and moving said hinged member in an opening direction against the bias of said closing spring whereby said bristles maintain constant their relationship with respect to said huller drum.

6. Cotton gin as claimed in claim 5, said adjusting means comprising a lever for translating the axis of said huller drum bodily away from said saws, a shaft extending transversely of said outer breast adjacent the inner side of said hinged member, cams on said shaft engaging

said hinged member for urging it in an opening direction against the bias of its closing spring, linkage between the axis of said huller drum and said shaft for turning the latter when said axis is translated, and a hand lever for operating said linkage.

7. Cotton gin of the huller type having inner and outer breasts defining between them a roll box, the outer breast having side walls and a lower rear wall including the huller ribs, and having bottom and forward enclosing structure, the lower parts of said side walls cooperating with said lower rear wall and said bottom and forward enclosing structure to form a hulling chamber having its mouth in a downwardly and forwardly inclined plane, a huller drum in said hulling chamber cooperating with gin saws projecting between said ribs and a conveyor in said hulling chamber below said huller drum, said outer breast having an upper rear wall in the path of cotton received from a feeding means and inclined so as to direct the cotton in a trajectory which in the absence of opposing structure will by-pass the mouth of said hulling chamber, a front for said outer breast pivotally suspended at its top at a point above said mouth having an inwardly and downwardly inclined baffle on its inner side for deflecting the column of cotton into said mouth when said front is closed, said front being swingable outwardly to a non-obstructing position permitting the cotton to by-pass said mouth, said enclosing structure including a screen beneath said conveyor and an outwardly swingable member hinged at its lower end adjacent said screen, having its upper end portion inwardly and downwardly directed adjacent the lower end of said baffle when said front and said hinged member are closed, forming substantially a continuation of said baffle, a bristle board carried by the upper end portion of said hinged member having its bristles in operative proximity to said huller drum, a spring biasing said hinged member towards its closed position, and means for simultaneously adjusting said huller drum away from said saws and moving said hinged member in an opening direction against the bias of said closing spring whereby said bristles maintain substantially constant their relationship with respect to said huller drum.

8. Cotton gin as claimed in claim 7, said adjusting means comprising a lever for translating the axis of said huller drum bodily away from said saws, a shaft extending transversely of said outer breast adjacent the inner side of said hinged member, cams on said shaft engaging said hinged member for urging it in an opening direction against the bias of its closing spring, linkage between the axis of said huller drum and said shaft for turning the latter when said axis is translated, and a hand lever for operating said linkage.

9. Cotton gin of the huller type having inner

and outer breasts defining between them a roll box, the outer breast having side walls and a lower rear wall including the huller ribs, and having bottom and forward enclosing structure, the lower parts of said side walls cooperating with said lower rear wall and said bottom and forward enclosing structure to form a hulling chamber having its mouth in a downwardly and forwardly inclined plane, a huller drum in said hulling chamber, said outer breast having an upper rear wall in the path of cotton received from a feeding means and inclined so as to direct the cotton in a trajectory which in the absence of opposing structure will by-pass the mouth of said hulling chamber, a front for said outer breast pivotally suspended at its top at a point above said mouth, for deflecting the column of cotton into said mouth when the front is closed, said front being swingable outwardly to a non-obstructing position permitting the cotton to by-pass said mouth, said enclosing structure including an outwardly swingable portion hinged at its lower end, having its upper end portion inwardly and downwardly directed and adjacent the lower end of said front when closed, forming a continuation of said front.

10. Cotton gin as claimed in claim 9, including a bristle board carried by said upper end portion of said hinged member having its bristles in operative proximity to said huller drum.

11. Cotton gin of the huller type having inner and outer breasts defining between them a roll box, the outer breast having side walls and a lower rear wall including the huller ribs, and having bottom and forward enclosing structure, the lower parts of said side walls cooperating with said lower rear wall and said bottom and forward enclosing structure to form a hulling chamber having its mouth in a downwardly and forwardly inclined plane, a huller drum in said hulling chamber and a conveyor in said hulling chamber below said huller drum, said outer breast having an upper rear wall in the path of cotton received from a feeding means and inclined so as to direct the cotton in a trajectory which in the absence of opposing structure will by-pass the mouth of said hulling chamber, a front for said outer breast for deflecting the column of cotton into said mouth, said enclosing structure including a screen beneath said conveyor and an outwardly swingable member hinged at its lower end adjacent said screen, having its upper end portion inwardly and downwardly directed and adjacent the lower end of said pivoted front when said front is closed, forming substantially a continuation of said front.

12. Cotton gin as claimed in claim 11, including a bristle board carried by the upper end portion of said hinged member having its bristles in operative proximity to said huller drum.

JEFFREY J. WALLACE.
